UNITED STATES PATENT OFFICE.

JAMES J. GILSON, OF PHILADELPHIA, PENNSYLVANIA.

COVER FOR SEMISOLID BALLS.

Application filed January 22, 1924. Serial No. 637,632.

To all whom it may concern:

Be it known that I, JAMES J. GILSON, a citizen of the United States, residing at Philadelphia, in the county of Philadelphia 5 and State of Pennsylvania, have invented certain new and useful Improvements in Covers for Semisolid Balls, of which the following is a specification.

My invention relates to covers for semisolid balls, such as baseballs, and its objects 10 are to provide a cover and method of applying the same whereby the cover may be made with a minimum waste of material and the ball produced at low cost.

These objects, and other advantageous 15 ends which will be described hereinafter, I attain in the following manner, reference being had to the accompanying drawings in which—

Figure 1 is a view of a ball constructed 20 in accordance with my invention,

Figure 2 a modified form of Figure 1,

Figure 3 another form,

Figure 4 a modified form of Figure 3,

Figure 5 an enlarged fragmentary section 25 through a seam of the cover illustrating the manner in which the edges are sewed,

Figure 6 a view similar to Figure 5 illustrating the edges of the cover abutting 30 each other after being sewed,

Figures 7 and 8 are developed plan views 35 of a part of the cover shown in Figure 1, and

Figure 9 a developed plan view of a part 40 of the cover shown in Figure 3.

Referring to the drawings, 1 indicates a ball having any suitable filling such as 45 wound cord, felt or stuffed material, and covered by my improved cover 2. The cover is made in semi-spherical sections 3 and 4 50 sewed to each other at their edges 5 and 6 by stitching 7. In Figure 1, the semi-spherical sections comprise a pair of figure-8 pieces 9 and 10, the piece 9 being cut in half lengthwise to provide parts 11 and 12 and the piece 10 being cut in half crosswise to 55 provide parts 13 and 14. The parts 11 and 13 are sewed to each other at 15 to form the semi-spherical section 3 and the parts 12 and 14 are sewed to each other at 16 to 60 form the semi-spherical section 4.

In Figure 2, the semi-spherical sections 65 are made of one piece as shown at 3^a and 4^a. These sections may be molded into shape before being applied to a ball.

In Figure 3, I have shown the cover made

of quarter-spherical-sections 17, 18, 19 and 20 connected at their edges by stitching as shown at 21. Each of these quarter-spherical-sections are made up of similar parts 60 22 of a figure-8 cut in the form shown in Figure 9. These parts 22 are sewed at their edges 23 to form the quarter-spherical-sections.

In Figure 4, I have shown the quarter-spherical-sections in one piece as shown at 65 17^a, 18^a, 19^a and 20^a. These sections may be molded into shape before being applied to the ball.

The edges of the cover parts may be 70 stitched as shown at 7 in Figure 5 so that projecting flanges 24 are provided for protecting the stitching, or may be sewed so that the edges of the cover parts abut each other as shown at 25 in Figure 6. 75

The edges stitched as shown in Figure 5 provide a flange for protecting the stitching while the edges stitched as shown in Figure 6 produce a ball having a substantially flush surface and is particularly adapted for a baseball. 80

The method of applying my improved cover to a ball consists of cutting a pair of figure-8 pieces 9 and 10 in halves, one of the pieces being cut lengthwise and the 85 other crosswise as shown in Figure 8; then stitching the parts 11 and 12 shown in Figure 7 to the parts 13 and 14 shown in Figure 8 to form the semi-spherical sections 3 and 4, the stitching being preferably done 90 with a machine; then applying the semi-spherical sections to the ball, and stitching their edges 5 and 6. The edges 5 and 6, being in a plane passing through the center of the ball, are readily adapted for sewing 95 by a machine as disclosed in my application Serial No. 693,914, filed of even date herewith.

A cover made and applied to the ball in this manner reduces the manufacturing 100 cost because the component parts are of such shape that they may be cut with very little waste of material.

While I have described my invention as taking a particular form, it will be understood that the various parts may be changed without departing from the spirit thereof, and hence I do not limit myself to the precise construction set forth, but consider that I am at liberty to make such changes and 105 alterations as fairly come within the scope of the appended claims.

Having thus described my invention, what I claim as new and desire to secure by Letters Patent is:

- 5 1. A cover for balls comprising semi-spherical sections, each made up of inter-fitting parts of a figure-8 stitched together.
2. A cover for semi-solid balls comprising half figure-8 parts sewed to each other to form semi-spherical sections, and stitching connecting the edges of the sections to each other.
- 10 3. A cover for semi-solid balls comprising a pair of figure-8 pieces, one piece being cut in two parts crosswise and the other piece lengthwise, a stitching connecting the

edges of the parts to form semi-spherical sections, and stitching connecting the edges of the sections.

4. The herein described method of securing a cover on a ball consisting of cutting a figure-8 piece in half crosswise and another figure-8 piece in half lengthwise, sewing a cross-cut figure-8 part to a length-cut figure-8 part to form a pair of semi-spherical sections, placing the sections on a solid ball, and sewing their edges to each other.

In testimony whereof I have signed my name to this specification.

JAMES J. GILSON.
